UNITED STATES PATENT OFFICE.

JOSEPH SCHINHARL, OF NEW YORK, N. Y.

MOLD.

SPECIFICATION forming part of Letters Patent No. 732,966, dated July 7, 1903.

Application filed May 18, 1903.

Serial No. 157,542. (No model.)

To all whom it may concern.

Be it known that I, JOSEPH SCHINHARL, a citizen of Germany, residing at the city of New York, borough of Manhattan, county and State 5 of New York, have invented certain new and useful Improvements in Casting-Molds, of which the following is a specification.

The object of my invention is to provide a new and improved mold for casting pipe-sections—such as elbows, T's, cross-pieces, and the like—in iron, brass, and other metals for water, gas, steam, and other pipes, which mold is simple in construction, can be opened and closed very rapidly, and thus permits of 15 casting a large quantity of pieces in a very short time.

In the accompanying drawings, in which like figures of reference indicate like parts in all the figures, Figure 1 is a front view of my 20 improved casting-mold closed. Fig. 2 is a plan view closed. Fig. 3 is a vertical longitudinal sectional view. Fig. 4 is a horizontal sectional view on the line 4-4 of Fig. 3.

The mold is constructed with a base 1, to 25 the upper surface of which the rear mold-section 2 is detachably secured by means of a bolt 3, so as to permit of removing said section readily in case a different pattern is to be cast. By means of a bolt 4 a hinge-piece 30 5 is held on the rear edge of the rear mold-section 2, at the top thereof, and to said hinged piece 5 a top piece 6 is pivoted by means of a pivot-bolt 7, which top piece is provided with an aperture 8 for receiving a neck or extension 9 of the core 10, according to the shape 35 of the piece to be cast. The top piece is provided at its front end with a downwardly-extending lip 11 and also with a handle 12, to the free end of which a latch-bar 13 is pivot- 40 ed, which terminates in hook 14, for a purpose to be set forth hereinafter.

The front mold-section 15 rests loosely upon the base 1, on which it can slide in the direction toward and from the rear section 2, and 45 it is of the same height as said rear section, and the width from front to rear of said front section 15 at the top is such that when the top section is lowered the lip 11 of this top section will rest on the front of said front section 15. 50 The front and rear sections have their inner edges so molded and shaped as to conform to part of the outer surface of the piece to be

cast, and the bottom edge of the top section 6 is also shaped accordingly. The core is provided at its lower end with a centering 55 projection 16, which fits into a corresponding recess 17 in the inner edge of said front section 15. An elbow-lever 18 is pivoted to a jaw 19, projecting from the front of the base-plate, and is provided with longitudinal slots 60 20 in its lower forked member or arm, and through said slots a pin 21 passes, which is held in a jaw 22, projecting from the front section 15, at the bottom thereof. The lever 18 also has a laterally-projecting pin 23, which 65 can be engaged by the hook 14 on the lower end of the latch 13. At each side of the rear and front sections 2 and 15, which sections are in line in the direction from front to rear, a side section 24 is pivoted to the base 1 by means 70 of pivot-bolts 25, passing through the lower ends of said side sections and through lugs 26, projecting upward from the base. These side sections have their lower edges 27 rounded semicircularly concentric with the pivot- 75 pins 34, so that when these side sections are in vertical position they will rest snugly against the side faces of the front and rear sections 15 and 2, and the inner surfaces of said side sections are recessed or cut out to 80 conform to the outer surfaces of the article to be cast, as shown at 28 in Fig. 4. At the upper end of each recess 28 an inclined inlet-opening 29 is formed, which extends to the upper edge of the side section and serves as 85 a pouring-hole. A lever 30 is pivoted by a bolt 31 on the top section 6 and is provided at one end with a handle 32. This lever has two opposite notches 33 for receiving headed studs 34, projecting from the upper ends of 90 the side sections 24.

The operation is as follows: The proper rear section 2, front section 15, and side sections 24, according to the article to be cast, are secured, hinged, and mounted on the 95 base 1, the top section 6 having been hinged, by means of the hinge-piece 5, to the rear section. The latch-hook 14 is disengaged from the pin 23, the top section 6 is raised, and the lever 18 swung down, whereby the front section 15 is pulled to the front. The top section 6 is raised, the centering projection 9 of the core 10 is placed into the opening 8, and then the top section is swung down and be-

fore it arrives in its lowermost position the lever 18 is swung upward, whereby the front section 15 is pushed to the rear, and when all parts have assumed their proper position 5 the top section 6 can swing down into the position shown in Fig. 3 and is then locked in place by engaging the hook 14 of the latch-rod 13 with the pin 23 of the lever 18. The core 10 is now held in proper position and centered by its core projections 9 and 16 at opposite ends within the openings 8 and 17 of the top section 6 and front section 15, respectively. The side sections 24 are then swung up and the lever 30 turned on its pivot 31, so as to 10 cause the headed studs 24 to pass into the notches 33 of said lever 30, whereby the side sections are locked in place at the sides of the front, rear, and top sections. The molten metal is then poured in through the casting-openings 29 at the top and fills the space 15 between the core and the recesses in the several mold-sections. After the casting has been made the side sections are unlocked and swung down, the lever 18 is unlocked, 20 the top section is raised, the lever 18 is then swung down for the purpose of pulling the front section 15 to the front, and the casting can be removed and immediately thereafter another made in the manner described, and 25 so on.

Having described my invention, what I claim as new, and desire to secure by Letters Patent, is—

1. In a casting-mold, the combination with 35 a base, of a fixed rear section, a front section mounted movable toward and from the rear section, a top section mounted to swing toward and from the top of the front and rear sections, and side sections mounted to swing 40 up against the sides of said front, rear and top sections, substantially as set forth.

2. In a casting-mold, the combination with 45 a base, of a rear section fixed on the same, a front section movable on the base toward and from the rear section, a top section hinged to the rear section, said top section and front section having openings for receiving core-centering projections on the ends of the core, locking means for locking the front, rear and top 50 sections together, and side sections mounted to swing against the sides of the front, rear and top sections substantially as set forth.

3. In a casting-mold, the combination with 55 a base, of a rear mold-section on the same, a front mold-section movable on the base toward and from the rear section, a top section hinged

to the rear section, said top section and front section having recesses for receiving centering projections of the core and side sections mounted to swing against the sides of the rear, 60 front and top sections, substantially as set forth.

4. In a casting-mold, the combination with a base, of a rear mold-section on the same, a front mold-section movable on the base toward 65 and from the rear section, a top section hinged to the rear section, said top section and front section having recesses for receiving centering projections of the core, side sections mounted to swing against the sides of the rear, front 70 and top sections, a lever on the top section, and means on the free edges of the top sections for engagement with said lever, when said side sections are raised, substantially as set forth. 75

5. In a casting-mold, the combination with a base, of a rear mold-section thereon, a front mold-section movably mounted on the base, a top section hinged to the rear section, a latch-rod pivoted to the top section, a lever for 80 shifting the front section toward and from the rear section, and means for engaging said lever with the latch-rod, substantially as set forth.

6. In a casting-mold, the combination with 85 a base, of a rear mold-section thereon, a front mold-section movable toward and from the rear section, side sections, a lever pivoted to the base and provided with slots, a projection on the front section, and a pin on said projection extending into the slots of the lever, substantially as set forth.

7. In a casting-mold, the combination with a base, of a rear mold-section secured thereon, a front mold-section movable toward and from 95 the rear section, a top section, side sections, a latch-rod pivoted to the front of the top section, a lever pivoted to the base, which lever has slots, a projection on the front section, a pin in said projection, entering the 100 slots in the lever, and a projection on said lever for engagement with the latch-rod, substantially as set forth.

In testimony whereof I have signed my name to this specification, in the presence of 105 two subscribing witnesses, this 12th day of May, 1903.

JOS. SCHINHARL.
